UNITED STATES PATENT OFFICE

WILLIAM G. FRAZIER, OF PHILADELPHIA, PENNSYLVANIA

SHAVING OUTFIT

Application filed August 12, 1930. Serial No. 474,827.

This application is a continuation in part of and embodies improvements in my co-pending application for patent for shaving brush, filed February 25th, 1929 and given Serial No. 342,590.

The invention relates to toilet accessories, particularly to shaving kits or outfits, and has for its general object the provision of a self-contained kit having means for heating water for shaving purposes, the brush being of the fountain type whereby water may be applied initially to the face and subsequently for working up lather with the utmost ease and without any necessity for a large supply of water or for any dipping operation.

An important object of the invention is to provide a fountain shaving brush having associated therewith a water reservoir, self-contained means for applying heat to the reservoir for heating the water to a comfortable and proper temperature, together with a self-contained supply of soap in solid or stick form, these various elements being so arranged or disposed relatively to one another as to insure the maximum convenience and saving of time in use, the entire kit being of particular benefit to traveling men and others dwelling or working in places where the usual facilities are not available.

A more specific object of the invention is to provide a device of this character in which the heating feature involves the employment of a solidified alcoholic or other similar fuel, such as that known commercially as "Sterno", this particular substance being preferred as it does not run and will therefore not leak out of the container provided for its reception and storage.

Another object of the invention is to provide a combination device in which the heating unit may be omitted, if desired, and the space normally occupied thereby used to accommodate the stick or cake of soap.

Another object is to provide a device of this character having ventilating openings for admitting air necessary to support combustion of the fuel and equipped with means for closing the openings and sealing the joints to prevent evaporation of the volatile material from the fuel when the device is not in use.

but is simply being carried about, or for preventing drying out of the cake or stick of soap in the event that the heating unit is omitted and replaced by the soap and the holder therefor.

55

A very important object of the invention is to provide a fountain brush equipped with means for regulating the flow of water therethrough or for cutting off the flow so that a supply of water may be carried in the reservoir or boiler.

60

Another very important object is to provide a kit of this character embodying a novel soap holding means which will be capable of gripping a stick of soap which might vary to a certain extent from the ordinary diameter intended to be used, this gripping means being of such formation as to avoid mashing or mutilating the stick.

65

A further object is to provide an igniting device which forms part of and is normally contained in the kit but which is operable to light the solid fuel so that the user will not need to rely upon a match.

70

Another specific object is to provide a cap for enclosing the brush when the device is not in use, the cap being of such construction as to permit the brush to dry out and not become sour.

75

An additional object is to provide a kit of this type which will be simple and inexpensive to make, neat and attractive in appearance, easy and convenient to use, positive in action, efficient and durable in service, and a general improvement in the art.

80

To the attainment of the foregoing and other objects and advantages, the invention preferably consists in the details of construction and the arrangement and combination of parts to be hereinafter more fully described and claimed, and illustrated in the accompanying drawings in which:

85

Figure 1 is a side elevation of the device showing it in normal or closed position,

95

Figure 2 is a view partly in elevation and partly in section showing the device closed and with the brush enclosing cap removed,

Figure 3 is a side elevation showing the device opened up ready for use and illustrating

100

the soap and holder detached and the igniter in service,

Figure 4 is a longitudinal section through the complete device in closed position,

5 Figures 5, 6 and 7 are cross sections on the lines 5—5, 6—6, and 7—7, respectively, of Figure 4,

10 Figure 8 is a view partly in side elevation and partly in section showing the soap holder in normal condition,

Figure 9 is a section therethrough showing the parts disconnected.

15 Referring more particularly to the drawings I have shown the device as comprising three main parts indicated as a whole by the numerals 10, 11 and 12, all of which will be described and the relationship explained with particularity. The part 10 may be described briefly as a combined boiler or reservoir and 20 brush holder and it comprises a metallic shell 13 preferably constricted at one end where it is provided with an interiorly located collar 14 within which is detachably mounted the base portion 15 of a brush 16.

25 In the present instance the detachable connection is shown as consisting of screw threads but it should be distinctly understood that any other quick detachable connection may be provided the exact detail 30 being immaterial. It is preferable that the base 15 have an outstanding flange 17 overlying the constricted end of the shell or body to provide abutment means for a sealing gasket 18. Intermediate the ends of the shell 35 13 there is provided a transverse partition 19 defining a chamber 20 thereabove adapted to be filled, partially or entirely, with water to be used for shaving purposes. As it is intended that the brush be of the fountain 40 type, the base thereof is shown as provided with an opening or passage 21 so that the water within the compartment 20 may feed into and through the brush when the device is properly tilted. It is an important feature 45 that the flow be controllable and I therefore provide valve means which may conveniently be a plate 22 pivoted at 23 upon the end of the base of the brush and swingable thereover to cover or uncover the passage to the desired extent, it being preferable to provide a stop 24 against which the plate abuts when it is in position to close the passage entirely.

50 The water within the compartment or reservoir 20 is intended to be heated by means of a heating unit contained within the part or section 11, and in order to insure rapid heating of the water the partition 19 is preferably of upwardly convexed or dome shape 55 as indicated so as to increase its area.

55 The part 11 which contains the heating unit is simply a metallic shell of substantially cylindrical form and provided intermediate its ends with a partition 25 above which is 60 located and upon which rests a can or other

suitable receptacle 26 containing a solid fuel, for instance solidified alcohol. This can is preferably of the friction top type, though the top is not shown, so that it may be readily sold as a replacement when needed. By 70 making this can of this type it will necessarily have an inwardly extending flange 27 which will serve to prevent the running out of any of the fuel, indicated at 28, in the event that any portion of the fuel may be more or less liquid as is frequently the case at the 75 top of a freshly opened can.

The part 11 telescopes within the part 10 and the latter is formed with a circumferential series of openings 29 to permit the insertion of a match or the igniting device to be described for igniting the fuel when the part 11 is pulled down or out to uncover the openings 29, these openings also serving to permit the admission of air necessary to support combustion of the fuel. Ordinarily the parts 10 and 11 are held in closed relation as by means of a pin 30 on the latter engaging within a bayonet slot 31 in the former, or by pressed threads.

It is highly desirable to prevent evaporation of the volatile matter in the solid fuel, partly for reasons of economy, but principally to avoid the odor thereof permeating clothing or the like in a traveling bag, trunk or other receptacle in which the device may be stowed away while not in use. Clearly, the partition 25 prevents any escape in one direction. To provide sealing means at the top of the part 11 I employ a gasket 32 of any suitable material which will neither burn nor melt when the fuel is burning and the device is in use, this gasket fitting over the top edge of the can 26 and abutting against the bottom surface of the partition 19 at the outer edge thereof as clearly shown in Figures 2 and 4. When the device is not in use and the part 11 is shoved tightly into its closed relation to the part 10 this gasket will fit snugly and positively prevent the escape of any fumes or odor.

The part 12 constitutes the closure for the end of the part 11 and is constructed as a novel holder for a cake or stick of soap 33 which may be of a type in use for shaving purposes and which is intended to be specially made and standardized so as to be obtainable, from the proper source, when replacement is necessary. By constructing this holder in such manner that it will take only a stick or cake of a certain and possibly unusual diameter it is possible for the manufacturer of the kit to control the market in so far as replacement sticks are concerned. If this is not desired, the holder can be made more or less adjustable to take sticks of different diameters. The part 12 is herein disclosed as including a cap 34 exteriorly threaded, having an outstanding flange 35 constituting a finger grip and formed with a socket 30

36 within which is located a shell 37 closed at its bottom and including a flange portion or side wall which is split or slit at intervals, as shown at 38, to provide a plurality of 5 flexible tongues 39 which preferably lean in toward one another and which may have their extremities folded over or crimped upon themselves as at 40 partly for reinforcing purposes and partly to prevent the sharp 10 edges at the extremities from contacting with and mutilating the soap stick. The soap is of course located within the confines of the tongues 39 and the shell 37 is located within the socket 36. To maintain these parts in 15 assembled relation and to cause the tongues 39 to grip and hold the soap, I provide a clamping ring 41 which is threaded onto the cap 34 and which has a constricted smooth bore 42 cooperating with the tongues 39 to 20 force them into compressing engagement with the soap stick. This part 12 simply telescopes within the lower end of the section 11, the exterior of the ring 41 frictionally engaging the inner surface thereof.

25 When the device is not in use it is certainly advisable to protect the brush against dust and dirt. To accomplish this I provide an enclosing cap 43, formed as a metal shell closed at one end and open at the other and 30 adapted to be placed over the brush 16 with its open end frictionally engaged upon the part 10. To permit drying out of the brush after use so that the bristles will not become excessively soft and so that the brush will 35 not become sour, this cap is preferably provided with any desired number of perforations 44 of the same or different sizes located at spaced intervals.

Frequently a match may not be available 40 for igniting the fuel when the device is to be used and I therefore equip the kit or outfit with a self-contained igniter similar to those in common use by smokers. While the specific details are more or less capable of variation, 45 I have shown this device as comprising a bearing tube 45 provided at one end with a curved plate 46 conforming substantially to the curvature of the cap 43 and part 10, for a reason to be explained, and provided at its 50 other end with a frame 47 having a guide 48 therein within which is slidable a so-called "flint" or piece of sparking substance 49 urged by a spring 50 mounted on the frame 47 into engagement with a milled wheel 51 which is 55 mounted on a shaft 52 journaled within the sleeve 45. This shaft projects through and beyond the plate 46 and is equipped with a suitably roughened wheel 53 adapted to be twirled between the forefinger and thumb of 60 the user for producing a spark by friction of the wheel or disk 51 against the "flint" 49. In order that this igniter, shown in detail in Figure 5, will always remain in association with the remainder of the outfit as a permanent part thereof, I provide a storage com-

partment 54 at the closed end portion of the cap 43, this compartment opening out to one side of the cap so that the igniter may be easily removed and replaced. It should be noted that the frame 47 should be of such size 70 that it may be passed through either of the openings 29 when it is desired to ignite the fuel.

Assuming that the device has been constructed as above described, it will be understood that when the device is not in use the part 11 is telescoped into the part 10 and held thereto by the pin 30 and bayonet slot 31. At such a time the part 11 extends into the part 10 to a sufficient extent to cover the 80 openings 29. The gasket 32 performs its sealing function above described. The part 12 is of course contained within the part 11 between its open end and the partition 25, only the flange 35 projecting to serve as a 85 finger grip. The cap 43 is in telescopic engagement upon the part 10 and the igniter is stored within the compartment 54 with the curved plate 46 lying closely against the cap 43 and only the wheel 53 projecting. If 90 water be carried in the compartment or reservoir 20 it is intended that the plate 22 be swung so that it will close the passage 21. In such condition the device may be carried in the pocket or in a piece of luggage without 95 spilling of the water, drying out of the soap or evaporation of the fuel.

In the use of the device, the cap 43 must be removed so as to expose the brush. The operator grasps the flange 17 and unscrews 100 the brush from the collar 14 in order to fill the reservoir 20 with water to the desired extent, if the reservoir be empty, or so as to gain access to the plate 22 for the purpose of moving it to uncover the passage 21 to the 105 desired extent if the reservoir already contains water. In any event, assuming that there is water in the reservoir 20 and that the passage 21 is uncovered to the desired extent and that the brush is again screwed into place, the next step is to grasp the parts 10 and 11, rotate them slightly and at the same time pull them apart to a sufficient extent that the openings 29 will be uncovered 110 to give access to the fuel. The operator then 115 grasps the projecting wheel 53 of the igniter, pulls the igniter out of the compartment 54 and then inserts it through any of the openings 29. The igniter is easily held in position at this point by placing the thumb of 120 one hand against the curved plate 46 as shown in Figure 3. Taking care that the "flint" and the wheel 51 do not touch and become moistened by the fuel the operator 125 grasps the wheel 53 between his forefinger and thumb of the other hand and twirls it. The resultant spark between the wheel 51 and substance 49 will ignite the fuel 28, whereupon the igniter is withdrawn and replaced within its compartment 54. After 130

the fuel burns a very short time the water will be heated to the proper degree to be comfortable on the face and to be suitable for working up a lather. As soon as the heating has been carried out to the desired extent, the operator simply presses down upon the part 10 so that it will telescope over the part 11, the latter then closing the openings 29. As no air can then reach the burning fuel, the flame dies out almost instantly. The operator then grasps the device in his hand, tilts it into a more or less horizontal or downwardly inclined position and rubs the brush over his face. The heated water will then flow from the reservoir through the passage 21 into the brush which it will saturate and will of course be transferred to the face. After the face has been properly wetted, the operator grasps the projecting flange 35 of the soap holder and pulls it and the soap stick as a unit out of the part 11. The soap stick is then rubbed over the face until the desired quantity adheres, after which the soap and its holder are reinserted within the part 11. Again using the brush the operator works the soap into a lather which softens the beard in the well known manner and puts it in condition for shaving.

From the foregoing description and a study of the drawings it will be apparent that I have thus provided a very simply constructed and easily operated and adjusted device which will be of great benefit and convenience and which on account of its compactness and unitary nature will recommend itself particularly where the usual facilities are lacking there being, however, no restriction in this respect as the device is really more convenient than the usual equipment even though of the best. It is believed that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described my invention, what I claim is:

1. In a kit of the character described, the combination of a handle member formed with a water reservoir, a fountain brush carried by one end of the handle member and having valved communication with the reservoir, heating means within the handle member, the handle member being formed of relatively movable sections movable to give access to the heating means and to admit air

thereto for supporting combustion, and a closure member for the other end of the handle member formed as soap-holding means.

2. A kit of the character described comprising the combination of a handle member formed of telescopically engaged sections, one section being formed with a water reservoir and equipped at one end with a fountain brush communicating with the reservoir, fuel holding means within the other section, air admission means in the first named section exposed upon relative movement of the sections longitudinally, a soap holding member constituting a closure for the second named section, and a cap detachably telescopically engaged upon the first named section for enclosing the brush. 70 75 80

3. A kit of the character described comprising the combination of a handle member formed of telescopically engaged sections, one section being formed with a water reservoir and equipped at one end with a fountain brush communicating with the reservoir, fuel holding means within the other section, air admission means in the first named section exposed upon relative movement of the sections longitudinally, a soap holding member constituting a closure for the second named section, and a cap detachably telescopically engaged upon the first named section for enclosing the brush, said cap being formed with a compartment opening out to one side, and a fuel igniting device removably mounted within said compartment. 85 90 95

4. In an outfit of the character described, the combination of a handle member provided with a water reservoir and equipped at one end with a fountain brush communicating therewith, a fuel container mounted within the handle member, the handle member being formed of relatively movable sections one provided with openings exposed upon relative movement, a cap detachably engaged upon the handle member and formed with a compartment, and an igniting device removably mounted within said compartment and insertible through one of said openings for igniting the fuel. 100 105 110

5. In a kit of the character described, a tubular shell open at one end, a storage compartment within said open end, and removable means for holding a stick of soap within said compartment comprising a closure member removably, telescopically engaged within said open end and formed with a socket surrounded by an upstanding flange, a member removably mounted within the socket and having a plurality of resilient tongues thereon for embracingly engaging a stick of soap, and a ring detachably engaged upon said flange and co-acting with said tongues to force the same inwardly. 115 120 125

6. In a kit of the character described, a tubular shell open at one end, and means for detachably holding a stick of soap within 130

said open end comprising a cap telescopically engaged within the open end and formed with a central socket surrounded by an exteriorly threaded flange, a shell member seated within the socket and having a frustoconical wall formed to define a series of resilient tongues, the second named shell member being adapted to receive a stick of soap, and a ring interiorly threaded and screwed upon said flange, the ring having a constricted bore cooperating with said tongues to force the same inwardly into clamping engagement with the soap.

In testimony whereof I affix my signature.

WILLIAM G. FRAZIER.
